UNITED STATES PATENT OFFICE.

JAMES EASTWICK, OF FYNING WOOD, ENGLAND.

MAGAZINE FOR SMALL-ARMS.

1,157,654.

Specification of Letters Patent. Patented Oct. 19, 1915.

Application filed June 15, 1915. Serial No. 34,293.

To all whom it may concern:

Be it known that I, JAMES EASTWICK, a subject of the King of Great Britain, residing at Fyning Wood, in the parish of Rogate, in the county of Sussex, England, have invented new and useful Improvements in Magazines for Small-Arms, of which the following is a specification.

This invention relates to rotary magazines for automatic and other rifles which are worked by, and therefore necessarily synchronize with, the longitudinal motion of the bolt.

It is specially adapted for use with a weapon such as is described in my patent specification No. 1,109,910, of September 8, 1914.

In order that my invention may be more readily understood I will describe it with reference to the accompanying drawings Figure 1 of which is a longitudinal section, Figs. 2, 3, 4, 5 and 6 are cross sections on the lines A—A, B—B, C—C, D—D and E—E of Fig. 1, Fig. 7 is a plan, Fig. 8 a horizontal section on the line F—F of Fig. 2, Fig. 9 an underside view, Figs. 10 to 15 show details. Fig. 16 is a central vertical longitudinal section of the weapon with the breech bolt in place, the magazine being unloaded. Fig. 17 is an underside view of the bolt and weight removed from the weapon; and Fig. 18 is a similar view of a modification. Fig. 19 is a part section showing a clip of cartridges in position for loading the magazine; and Fig. 20 is an enlarged detail.

1 is the magazine casing on the bottom of which are pivoted at 2, 2 two bars 3, 3 the front ends of which are kept apart by a spring 4. The front and rear ends of these bars normally rest above suitable bearings or shoulders a on the gun. By pressing together with the fingers two knobs a^1 which project downward from the front portions of the bars, the ends of the bars are removed from above the bearings a so that the magazine can drop out of the gun.

In the front and rear walls of the casing is journaled a spindle 5 to which is keyed a drum 6 adapted to receive five cartridges b ; the drum is fitted with transverse diaphragms 7, 7 which keep the cartridges in their proper relative positions. The spindle 5 carries toward its rear extremity two ratchet wheels 8, 9 which are turned step by step each time the bolt is actuated. As shown in Figs. 5, 10 and 11 the teeth of

the wheels are engaged by two bell crank levers 10, 11 pivoted to the rear wall of the casing and turned on their pivots by two transverse bars 12, 13 adapted to be transversely reciprocated by the longitudinal movements of the bolt d or the gear connected with it in a manner similar to that described below. After the bolt has been withdrawn clear of the magazine opening e in 65 the frame f the last part of the rearward movement thereof causes the bell crank 10 to engage a tooth on the wheel 8 and to turn the spindle 5 through a small angle. The first part of the return movement of the bolt causes the bell crank 11 to engage a tooth on the wheel 9 and thus to turn the spindle and with it the drum sufficiently to raise a cartridge into a position in which it will be caught by the bolt and thrust forward. 75

In Figs. 12, 13, 15, 16, 17, 19 and 20 I have shown modified mechanism by which the same movements of the spindle can be accomplished. Here the movements of the 80 wheels are effected by teeth 14, 15 on a bar or plate 16 which can be slid transversely on guide pins 17 by a cross bar 18 actuated by inclines d' on the weight h . The spindle 5 though it rotates with the drum is capable of an independent longitudinal motion. In ordinary working the two are kept in the same relative position by a spring 19. At the rear of the spindle is a vertical cross bar 20 having at its upper end an inclined plane 90 21 and at its lower end a surface 201 against which the cut-off hereinafter described impinges. When the last cartridge has been fired the next initial movement of the drum causes a stud 23 carried by an arm 22 on 95 the drum to bear against a part 24 of the frame, which prevents further rotation of the cartridge drum. At this time the tooth 15 of the plate 16 is in engagement with the double tooth 91 of the ratchet 9 as herein-after described. Since the plate 16 is rigidly carried by the sliding bar 18, transverse movement of the bar 18 is prevented and the ends thereof being in engagement with the inclines d' on the weight h , the bolt is held 100 in its backward position. Then, when a clip with new cartridges is placed in position, it impinges against the inclined plane 21 and presses back the cross bar 20 and with it the spindle 5 sufficiently to free the ratchet 110 wheels from the bell cranks 10, 11 or the teeth 14, 15 of the plate 16, as shown in Fig.

19, compressing the spring 19 at the same time. The cartridges can now be pressed into the magazine, the drum and spindle rotating backward to admit them, the clip 5 meanwhile keeping back the bolt. When the magazine is refilled, the spring 19 brings the ratchet wheels into gear again as the clip is removed and the action proceeds as before.

13 When the magazine is full the cartridges are in the position shown in Fig. 2, the ratchet wheels being in that shown in Figs. 10 and 13. When the clip is removed the forward movement of the bolt brings the 15 inclines d' into engagement with the bar 18 which produces a right to left movement of the plate 16 (or a corresponding movement of the bell crank 11) which rotates the drum 50°. This raises the first cartridge into position for loading. On the next movement 20 of the bolt backward a left to right movement of the plate 16 takes place which causes a rotation of 20°. The return of the bolt produces a rotation of 50° and so on until the last cartridge is raised. Then the 25 next backward movement of the bolt produces, owing to the spacing of the teeth, a rotation of 10° only and at the commencement of the forward movement the tooth 15 catches on the notched or double tooth 91 of ratchet wheel 9 and the whole is locked with the bolt in its back position.

The cut-off is an eccentric 25 placed below the base of the magazine (see Fig. 9). 35 When rotated into the proper position it presses back the cross bar 20. This frees the ratchet wheels from the bell cranks as before described and so leaves the bolt free to work the transverse bars 12, 13 without 40 affecting the magazine. But the cut-off presses back the spindle farther than the clip does and this further pressure causes notches or teeth 26 on the spindle to engage corresponding studs or teeth 27 on the casing of the magazine and so prevents all rotation (see Fig. 6). On the cut-off being 45 rotated back the spring 19 brings the ratchet wheels into gear once more. Figs. 19 and 20 show clearly the intermediate position of 50 the wheels 8 and 9 into which they have been pushed back by the clip so far that they are out of engagement with the teeth 14, 15 but not so far that the teeth 26 engage the fixed teeth 27.

55 I place in the chamber g of the rifle a plunger 28 which presses against a bell crank 29 pivoted to the gun and this bell crank in its turn presses against a lever 30 which is pivoted to the magazine casing and 60 in its turn presses against the head of the spindle 5. When a cartridge is in place the plunger 28 is pressed down and the spindle is pressed back to the same extent as by the cut-off; the result is that the magazine can 65 only work when the chamber is empty and

thus all risk of double loading is avoided. When the cartridge is extracted the spring 19 in bringing back the ratchet wheels into gear presses up the piston again.

31 is a lever working with the bell crank 70 29 and gearing into an index bar 32 fitted in the receiver so that the index bar rises or falls as the piston falls or rises and thus indicates at once in ordinary working whether the weapon is loaded or not. These 75 parts are shown separately in Fig. 14. In hand loading, when the cut-off is in use and consequently the spring 19 compressed, the index bar works by its own weight or in case of doubt may be tested with the finger. 80 It will be understood that the index bar may carry or actuate any convenient form of index.

At the front of the spindle is a wheel 33 with teeth or friction surface actuating a 85 second wheel 34 with numbers on it and so arranged that as the spindle works the number on the wheel corresponding with the number of cartridges in the magazine appears in the proper position opposite an 90 orifice 35 in the base plate so as to indicate the number of cartridges in the magazine, whether the breech be open or not.

When any danger to the ammunition in the magazine from the shock of firing or 95 the motion of the piece is apprehended, the diaphragms 7, 7 on the drum are arranged so that together with corresponding ribs 36 on the casing they grasp the case by its run and shoulder and also the bullet near its 100 nose and so keep case and bullet secured in their relative positions. If two or more forms of bullet are used the grasp on the bullet must be arranged at some common point; the best way of doing this (in cases 105 where such a course is admissible) is to provide a shallow cannelure 37 on the bullet in which a rib and diaphragm engage. The effect of the ribs and diaphragms is continued by corresponding ribs or projections 110 38 in the opening in the frame f through which the cartridges rise so that the uppermost cartridge is secured as well as those in complete contact with the drum. In the design shown the uppermost cartridge cannot 115 fall out during a march with the breech open, but in cases where there is any such risk a catch 39 is formed on the transverse bar 12 or 16 which, when the bolt is fully drawn back and the bar hard over, holds the 120 rim of the cartridge and on the commencement of the return movement frees it before the ratchet wheels, spindle and drum begin to work.

Dispersing is provided for by forming 125 the spindle in two pieces screwing into each other as shown at 40 in Fig. 1. On removing the magazine from the stock and unscrewing the spindle, the drum, bar and spring fall out of their places.

Having thus described all the parts concerned in the present invention I will describe sufficiently to enable any person skilled in the art to understand the operation of such parts, a weapon as in Patent No. 1,109,910 and having my invention applied to it, as shown in Fig. 16.

The barrel A is screwed into the chamber g forming part of or rigidly attached to the frame f and at its fore end, which is not shown, it is secured to the stock in any convenient way permitting the barrel to move through a small distance relatively to the stock.

C is a bolt carrier inclosed within the weight h and which carries the bolt d having on its front end locking lugs D adapted to enter grooves E in the chamber so that the bolt can be locked thereby.

F is a firing pin passing axially through the bolt. Surrounding the firing pin is a firing spring G and also an unlocking spring H, these two springs being kept apart, so that they may not rub one upon the other, by a sleeve I extending rearward from the bolt carrier. When the piece is fired the weight lurches forward relative to the rest of the mechanism, or more strictly remains stationary, owing to its inertia, and does not partake in the first portion of the recoil, and thereby compresses the springs G and H. The firing pin is thereupon locked to the weight so that the spring G cannot expand until the trigger is again pulled to fire, but the spring H immediately expands and therefore the weight is thrown backward again carrying with it the firing pin. This rearward motion of the firing pin turns, through the lands and rifled grooves, the bolt in its bolt carrier and so forces the lugs D and the bolt is therefore free to move rearward out of the receiver, and the weight, bolt carrier, etc., move rearward along the raceway of the frame f.

The last part of the rearward motion of the bolt causes the inclines d' (seen in Figs. 17 and 18) to actuate the bell crank 10 or the plate 16 as already described to rotate the magazine through a small angle and the first part of the return movement (due to parts not shown but well understood) causes the bell crank 11 or the plate 16 to turn the magazine sufficiently to raise a cartridge into a position in which it will be caught by the bolt and thrust forward. Moreover at the commencement of recoil and during the lurch of the weight, the barrel, frame f and magazine have recoiled relatively to the stock and in so doing have compressed a recoil spring J arranged between the rear block K and the casing of the magazine. This spring is of such a strength that it expands again during the backward travel of the weight so that the frame f is urged forward relatively to the

stock by the spring while the weight is traveling rearward relatively to the stock by the spring H coupled with the effect of recoil, the result of these movements being an increase of power in the weight.

The casing of the magazine is rigidly attached to the frame f so as to slide with it.

The trigger gear is attached to the frame f and is connected with the trigger L by a bar M.

A retaining clutch N is attached to the raceway by a pivot O so that when the weight and the frame f are in their forward positions the weight is secured to the frame but on the recoil before the backward motion of the weight begins the clutch is removed and then cannot return to its place until the weight and frame f are again in their forward positions. This clutch is so arranged as also to secure the raceway to the casing and is operated by the trigger.

The trigger L presses by means of a bell crank P against the arm Q of the retaining clutch N. In the uncocked position in addition to the bolt being locked home, the weight h is held by a tooth R of the retaining clutch and the end S of the clutch rests against the rear block K. The weight is thus secured to the raceway and the raceway to the stock. On pulling the trigger the arm Q is pressed back, the tooth R is lowered but not sufficiently to release the weight altogether and the end S of the clutch is raised so that the sloping surface U is placed against a corresponding slope V on the rear block K. At the same time the bar M is drawn back, the trigger spring W is partly compressed, a bell crank X pivoted to the magazine casing is moved and a plunger Y is thereby lifted until it comes nearly against the front end of the clutch N. The upper end of the plunger now presses up the forward end of the sear Z, thus throwing the sear out of the bent l', on the firing pin F and the piece fires. It is this sear which catches the bent when the weight lurches forward and locks the firing pin to the weight so keeping the spring G compressed as referred to above. On the commencement of recoil the incline U is forced against the slope V, the spring W is further compressed, a spring flap x on the bell crank X is freed from the plunger Y, the tooth R is lowered out of the way of the rearward travel of the weight and the front end of the clutch N presses down the plunger Y into its original position. A tooth z on the sear when the latter is out of bent enters a recess z' in the frame f so that at the end of the forward lurch the tooth is forced backward and the sear raised into bent. The whole mechanism is now free to move until both the raceway f and the weight h return to the positions shown. Then the spring W rotates the clutch N on its pivot into the posi-

tion shown and at the same time moves back the bell crank X, the flap α opening and so slipping past the shoulder γ on the plunger and the piece is ready to fire again.

5. What I claim is:—

1. In a small arm, the combination with a barrel having a chamber at its rear end provided with lugs, of a longitudinally moving bolt having lugs adapted to engage corresponding lugs in the chamber, a part adapted to be transversely reciprocated by the movements of the bolt, a ratchet adapted to be rotated by the reciprocating part and a magazine fast with the ratchet.
15. 2. In a small arm, the combination with a barrel having a chamber at its rear end provided with lugs, of a longitudinally moving bolt having lugs adapted to engage corresponding lugs in the chamber, a toothed plate adapted to be transversely reciprocated by the movements of the bolt, a ratchet adapted to be rotated by the plate and a magazine fast with the ratchet.
25. 3. In a small arm, the combination of a longitudinally moving bolt, a toothed plate adapted to be transversely reciprocated by the movements of the bolt, two ratchet wheels, the one adapted to be rotated by movements in one direction of the plate and the other adapted to be rotated in the same direction by movements in the other direction of the plate and a magazine fast with the ratchet wheels.
35. 4. In a small arm, the combination of a longitudinally moving bolt, a part adapted to be transversely reciprocated by the movements of the bolt, two ratchet wheels, the one adapted to be rotated by movements in one direction of the reciprocating part and the other adapted to be rotated in the same direction by movements in the other direction of such part and a magazine fast with the ratchet wheel.
45. 5. In a small arm, the combination of a longitudinally moving bolt, a part adapted to be transversely reciprocated by the movements of the bolt, a ratchet wheel adapted to be rotated by the reciprocating part, a spindle secured to the ratchet wheel, a magazine adapted to be rotated by the spindle, and means adapted to be actuated by the insertion of a clip of cartridges for moving the ratchet wheel rearward so as to free it from the actuating mechanism.
55. 6. In a small arm, the combination of a longitudinally moving bolt, a part adapted to be transversely reciprocated by the movements of the bolt, a ratchet wheel adapted to be rotated by the reciprocating part, a spindle secured to the ratchet wheel, a magazine adapted to be rotated by the spindle, means adapted to be actuated by the insertion of a clip of cartridges for moving the ratchet wheel rearward so as to free it from the actuating mechanism, and a spring

adapted on the withdrawal of the clip to move the ratchet wheel forward again into its operative position.

7. In a small arm, the combination of a longitudinally moving bolt, a part adapted to be transversely reciprocated by the movements of the bolt, a ratchet wheel adapted to be rotated by the reciprocating part, a spindle secured to the ratchet wheel, a magazine adapted to be rotated by the spindle, a spring adapted to move the spindle forward relatively to the magazine, a vertical cross bar on the rear of the spindle and an eccentric adapted to move the cross bar rearward.

8. In a small arm, the combination of a longitudinally moving bolt, a part adapted to be transversely reciprocated by the movements of the bolt, a ratchet wheel adapted to be rotated by the reciprocating part, a magazine fast with the ratchet wheel, and means adapted to be actuated by the presence of a cartridge in the chamber for preventing the rotation of the magazine.

9. In a small arm, the combination of a longitudinally moving bolt, a part adapted to be transversely reciprocated by the movements of the bolt, a ratchet wheel adapted to be rotated by the reciprocating part, a spindle secured to the ratchet wheel, a magazine adapted to be rotated by the spindle, a spring adapted to move the spindle forward relatively to the magazine, a vertical plunger projecting into the chamber and adapted to be depressed by the insertion of a cartridge into the chamber and means whereby the depression of the plunger prevents the rotation of the magazine.

10. In a small arm, the combination of a longitudinally moving bolt, a part adapted to be transversely reciprocated by the movements of the bolt, a ratchet wheel adapted to be rotated by the reciprocating part, a magazine fast with the ratchet wheel and means for indicating when a cartridge case is in the chamber.

11. In a small arm, the combination of a longitudinally moving bolt, a part adapted to be transversely reciprocated by the movements of the bolt, a ratchet wheel adapted to be rotated by the reciprocating part, a magazine fast with the ratchet wheel and means for indicating the number of cartridges in the magazine.

12. In a small arm, the combination of a longitudinally moving bolt, a magazine, a spindle adapted to rotate the magazine but capable of longitudinal movement through it, a pair of ratchet wheels fast on the spindle, and means whereby the longitudinal movements of the bolt rotate the ratchet wheels.

13. In a small arm, the combination of a longitudinally moving bolt, a magazine, a spindle adapted to rotate the magazine but capable of longitudinal movement through

it, a pair of ratchet wheels fast on the spindle, a transverse plate, means carried by the bolt for reciprocating the plate transversely and a pair of teeth on the plate adapted one to engage one of the ratchet wheels and the other, the other.

14. In a small arm, the combination of a longitudinally moving bolt, a magazine, a spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely and a pair of teeth on the plate adapted one to engage one of the ratchet wheels and the other, the other.

15. In a small arm, the combination of a longitudinally moving bolt, a magazine, a spindle adapted to rotate the magazine and capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, and means adapted to be actuated by the insertion of a clip of cartridges for moving the ratchet wheels rearward out of engagement with the teeth on the plate.

16. In a small arm, the combination of a longitudinally moving bolt, a magazine, a spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, a vertical cross bar on the rear of the spindle and an eccentric adapted to move the cross bar rearward.

cross bar rearward.

17. In a small arm, the combination of a longitudinally moving bolt, a magazine, a spindle adapted to rotate the magazine, a spindle adapted to rotate the magazine, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, a vertical cross bar on the rear of the spindle adapted to be moved rearward by the insertion of a clip of cartridges, and an eccentric adapted to move the cross bar rearward.

18. In a small arm, the combination of a longitudinally moving bolt, a magazine, a

spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, and means adapted to be actuated by the insertion of a cartridge into the chamber for moving the spindle rearward. 70 75

19. In a small arm, the combination of a longitudinally moving bolt, a magazine, a spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, a vertical plunger projecting into the chamber and adapted to be depressed by the insertion of a cartridge into the chamber and means whereby the depression of the plunger prevents the rotation of the magazine. 80 85 90

20. In a small arm, the combination of a longitudinally moving bolt, a magazine, a spindle adapted to rotate the magazine but capable of longitudinal movement through it, a pair of ratchet wheels fast on the spindle, means whereby the longitudinal movements of the bolt rotate the ratchet wheels, and means actuated by the rotation of the spindle for indicating the number of cartridges in the magazine. 95 100

21. In a small arm, the combination of a longitudinally moving bolt, a magazine, a spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, and means actuated by the rotation of the spindle for indicating the number of cartridges in the magazine. 105
110
115

22. In a small arm, the combination of a longitudinally moving bolt, a magazine, a 120 spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, a vertical cross bar on the rear of the 125 130

spindle adapted to be moved rearward by the insertion of a clip of cartridges, an eccentric adapted to move the cross bar rearward, a vertical plunger projecting into the chamber and adapted to be depressed by the insertion of a cartridge into the chamber and means whereby the depression of the plunger moves the spindle rearward.

23. In a small arm, the combination of a longitudinally moving bolt, a magazine, a spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, a vertical cross bar on the rear of the spindle adapted to be moved rearward by the insertion of a clip of cartridges, an eccentric adapted to move the cross bar rearward, a vertical plunger projecting into the chamber and adapted to be depressed by the insertion of a cartridge into the chamber, means whereby the depression of the plunger moves the spindle rearward and means actuated

by the rotation of the spindle for indicating the number of cartridges in the magazine.

24. In a small arm, the combination of a longitudinally moving bolt, a magazine, a spindle adapted to rotate the magazine but capable of longitudinal movement through it, a spring adapted to move the spindle forward relatively to the magazine, a pair of ratchet wheels fast on the spindle, a transverse plate, means carried by the bolt for reciprocating the plate transversely, a pair of teeth on the plate adapted one to engage one of the ratchet wheels and the other, the other, a vertical cross bar on the rear of the spindle adapted to be moved rearward by the insertion of a clip of cartridges, an eccentric adapted to move the cross bar rearward, a vertical plunger projecting into the chamber and adapted to be depressed by the insertion of a cartridge into the chamber, means whereby the depression of the plunger moves the spindle rearward, means actuated by the rotation of the spindle for indicating the number of cartridges in the magazine, and means for indicating when a cartridge case is in the chamber.

JAMES EASTWICK.
